Attorney.

UNITED STATES PATENT OFFICE.

WILLIAM J. DUVALL, OF ST. LOUIS, MISSOURI, ASSIGNOR TO SMITH & DAVIS MFG. CO.,
OF ST. LOUIS, MISSOURI, A CORPORATION OF MISSOURI.

EXTENSION OR PULL-OVER BED.

Application filed March 21, 1924. Serial No. 700,854.

To all whom it may concern:

Be it known that I, WILLIAM J. DUVALL, a citizen of the United States, residing at St. Louis, in the State of Missouri, have invented certain new and useful Improvements in Extension or Pull-Over Beds, of which the following is a specification.

My invention has relation to improvements in beds and is directed more particularly to combination day-beds and couches, and consists in the novel features of construction more fully set forth in the specification and pointed out in the claim.

The object of the present invention is to provide a day-bed having two superposed sections, the upper of which may be swung outwardly and downwardly to a position adjacent to and in the same plane with the lower section to form a couch of twice the width of the normal day-bed. A further object is to provide a combined day-bed and couch of rigid though simple construction, and one having suitable space between the superposed sections for the bedding. Further and other advantages will be better apparent from a detailed description of the invention in connection with the accompanying drawings, in which—

Figure 1 is a top plan of my improved bed with the sections in extended position to form a couch, parts being broken away; Fig. 2 is an end elevation of the bed in extended position; Fig. 3 is a side elevation of the extended bed; Fig. 4 is an enlarged end elevation of the bed with the sections in superposed position to form a day-bed; and Fig. 5 is an enlarged side elevation of the corner piece on the detachable head and foot pieces that cooperates with a complementary corner piece on the legs of the bed; Fig. 6 is a modified form of the invention.

Referring to the drawings A and B represent the respective bed sections, the former the main supporting section and the latter the swinging or pull-over section connected in parallelism to the main section by two pairs of links to more fully hereinafter appear. The main section A is provided with legs 1, 1 at each end thereof, to the upper ends of which is secured an end rail 2 a short distance below which the legs are connected by an angle bar 3, and across the corners between the legs 1 and end rail 2 are suitable brace members 4, 4. A side rail 5 is secured to and connects the legs 1, 1 on

each side of the main section A, said side rail being disposed in a plane slightly below the end rails 2, 2. A link fabric 6 is stretched between the end rails 2, 2 to which it is secured by a plurality of helical springs 7 as well understood in the art.

The pull-over section B is provided with legs 8 and 8' at each end thereof, to the upper ends of which is secured an end rail 9, and across the corners between the legs 8, 8' and end rail 9 are suitable braces 10, 10. It will be observed (Figs. 2 and 4) that the legs 8, 8, which are on the same side of section B, are of the same length as legs 1, 1 of section A, and legs 8', 8', also on the same side, are considerably shorter. The reason for this will be readily apparent in the description of the operation of the invention. Legs 8, 8 are connected by a side rail 11, and legs 8', 8' are connected by a side rail 12. A link fabric 13 is stretched between end rails 9, 9 to which it is secured by a plurality of helical springs 14, 14.

The section B is connected to section A in parallelism by a pair of links 15, 16 at each end of said sections. Each link 15 is pivotally connected to an angle bar 3 at about the center thereof and to the overhanging end 9' of an end rail 9, the links 15, 15 at the respective ends of said sections being connected by a rod 17 which has a clamp 18 secured to it near each end, to which are secured the inner ends of a pair of balance springs 19, 19, the opposite ends of said springs being secured to side rails 5, 5 of the main section A. The links 16, 16 are also pivotally secured to bar 3 and end rail 9 in parallelism with links 15, 15 although links 16 are bent so as to clear the inner side rail 5 when the sections are extended (Fig. 2).

When the sections A and B are in superposed position to form a day-bed (Fig. 4) it will be observed that the legs 8', 8' of section B rest on end rails 2, 2 of section A and legs 8, 8 rest on angle brackets 20, 20 secured to adjacent legs 1, 1, and at the same time the springs 19 on the side toward which section B must be moved to extend it are under tension, which will assist the operator in extending the bed. Now as the section B is pulled up over section A the tension on the springs 19 will become balanced as the section B is balanced on links 15 and 16. Just as soon as section B

is lowered past dead center tension will be placed on the opposite springs 19 to counter balance the weight of said section and this counter balancing spring tension will again 5 be at its maximum when section B is lowered to the floor (Fig. 2). When the section B is fully extended its legs 8, 8 will rest on the floor and the inner side of said section will be supported in the same plane with 10 section A by the links 15 and 16.

It will also be observed that when the sections are superposed (Fig. 4) there is considerable space between them, the purpose of which is to receive the bedding which is 15 folded over onto the main section before the pullover section is swung up.

If desired a back-rest 21 may be pivotally mounted at one end of section B, said back-rest being provided with its own fabric 22^a, and being adjustable by means of a U-shaped brace 22 the cross-bar 23 of which is adapted to rest in any pair of a series of notches *n* formed in Z-bars 24 secured to the sides of side rails 11 and 12.

25 The entire bed may also be supported by special head and foot pieces 24^a and 25 respectively (shown dotted, Fig. 3) if desired, suitable corner fasteners being provided for this purpose on the legs 1, 1 of the main section A. Each corner fastener 26 consists of 30 an angle bracket 26 riveted to the leg 1 from the outwardly projecting portion 26' of which bracket are two spaced pins 27, 27 provided with enlarged heads 28, 28. The 35 fasteners 26, 26 are adapted to cooperate with fasteners 29, 29 on the posts of the head and foot end, said fasteners consisting of angle brackets each having its inwardly projecting portion 29' provided with a slot 40 30 open at the upper edge of the bracket and a slot 31 below the slot 30, the slot 31 having a terminal enlargement 32.

In mounting the bed on the head and foot 45 pieces 24, 25 each end is raised to permit the heads 28 of the lower pins 27, to enter the enlargement 32 of slot 31, after which

the pins 27, 27 are dropped down into slots 30 and 31. The portion 29' of bracket 29 adjacent the slots 30, 31 is then wedged between the portion 26' of bracket 26 and the 50 heads 28 of the pins 27 to hold the bed and the head and foot pieces in firm engagement.

Referring now to Figure 6, it will be observed that the link 16 has connected to it a short link 33, said link 33 also being pivotally connected at *y* to the end rail 3 between the points of connection of links 16 and 15. A bracket rest 34 is fixed to the rail 3 just below the point of connection of links 16 and 33, (when said links are in normal position) the purpose of which rest is to support the link 16 as it swings outwardly in extending section B. A stop pin 35 is secured in the rail 3 just behind point *y*. Now, in order to make the space between sections A and B more accessible for bed clothes, section B may be tilted upwardly (dotted, Fig. 6) the links 16 and 33 assuming a position shown by the dotted lines and being arrested by the pin 35 which holds the 70 section B in this position until manually lowered.

Having described my invention, I claim:

A bed composed of two sections, one of said sections constituting a main or supporting section and the other an extension section, the latter being normally supported above the main section and in spaced relation therewith, and being movable through an arc to a position adjacent to and in the same plane with the main section, means for maintaining said extension section in parallelism with the main section throughout its entire arc of movement, and said last mentioned means being arranged to permit tilting said extension section upwardly in a direction opposite to that in which it moves when extended.

In testimony whereof I hereunto affix my signature.

WILLIAM J. DUVALL.
